UNITED STATES PATENT OFFICE.

LOUIS KOPPERSMITH, OF NEW YORK, N. Y.

PICTURE FRAME.

1,415,654.

Specification of Letters Patent.

Patented May 9, 1922.

Application filed April 20, 1921. Serial No. 462,826.

To all whom it may concern:

Be it known that I, LOUIS KOPPERSMITH, a citizen of the United States of America, residing at New York city, New York 5 county, New York, have invented a new and useful Picture Frame, of which the following is a specification.

My invention relates to an improved picture frame for so-called medallion photographs and the like. The object is to provide a construction which may be economically produced, the finished article being very easy of application or removal.

In the drawings:

15 Fig. 1 is a front elevation of a medallion with the frame applied.

Fig. 2 is an edge elevation of a portion of the medallion with a section of the frame in place.

20 Fig. 3 is a perspective view of a portion of the stock from which the frame is made.

Fig. 4 is an end elevation of said stock after the first operation.

Fig. 5 is a perspective view showing the 25 effect of bending the stock shown in Fig. 4 into circular form.

1 represents a medallion, which in this particular instance is oval in form, the edge being rounded. While the particular construction of the medallion is immaterial to this invention, it will be understood that such devices are usually in the form of a plaque with a convex front surface and a concave rear surface. The frame to which 30 my invention relates is made of a size to fit snugly upon the circumferential edge of the medallion. The front edge 2 of the frame is notched or serrated for the purposes hereinafter described. The rear edge 35 of the frame is unbroken. I make the frame by taking a flat strip of metal, one edge of which is notched or serrated, to provide the desired ornamentation as well as to slightly weaken the extreme edge of the 40 same, so that when the strip is transformed into the final shape of the frame, the outer edge will not tear. I first take this flat straight strip as shown in Fig. 3, and I then bend down the unbroken edge at substantially right angles as shown in Fig. 4. I then bend the strip into round or oval 45 form and bring the ends together and solder them. The bending of the strip into round or oval form produces a twist in the same 50 throughout its entire length so that the inner edge of the frame presents a groove or channel which will receive the rounded edge of the medallion. The circumference of the unbroken rear edge of the frame is slightly less than the circumference of the medallion, with the result that it is necessary to apply a little force in fitting the frame to the medallion, but this may be easily done since the rounded edge of the medallion permits the rear unbroken edge of the frame to be easily snapped thereover by finger pressure alone. When this is done, the frame will be held friction-tight in place, the ornamental serrated front edge of the frame 60 furnishing an artistic frame or finishing for the edge of the medallion as well as serving to prevent accidental disengagement therefrom. If desired, one or more decorative scrolls or tips 4 may be secured to the outer edge of the frame, but I wish 65 it to be understood that my invention is not limited to the application of such decorative additions. In the foregoing, it will be seen that the serrated edge of the frame 70 performs a double function, to wit, it provides the decorative means aforesaid, and it weakens that edge of the frame so that when the straight strip of right angular cross-section is bent into curved form, the 75 said weakened edge of the frame will stretch so as to permit of the twisting or distortion of the strip throughout its length to produce the inner channel adapted to receive the rounded edge of the medallion. It will be observed that the serrations 80 shown terminate short of the bottom of the channel. By my invention, such frames may be rapidly and economically produced, since it is possible to stamp out cheaply and rapidly the initial flat strip with one ornamental edge. The process of bending down the unbroken edge is exceedingly simple, and the final process of bending the angular strip into round or oval form and cutting off and soldering the butt ends may 85 90 also be quickly accomplished, and all at a very small expense, whereby it is possible to furnish a frame of an exceedingly attractive appearance which may be easily and quickly applied to the medallion without the exercise of any special skill, and without the employment of any additional clips or fastenings such as are usually employed in the securing of frames to similar articles of merchandise.

From the foregoing it will be seen that my invention relates not only to the finished

article, but to the process of forming the same.

What I claim is:—

1. A frame comprising a sheet metal strip angular in cross-section to provide a channel along its inner side, the outer edge of said strip being serrated, said serrations terminating short of the bottom of said channel.

10 2. A process of forming a frame, com-

prising, first forming a straight flat strip with one serrated edge, then bending the strip longitudinally at substantially right angles, then bending the strip transversely into curved form, simultaneously twisting 15 said strip to form a channel at the inner side, and then uniting the ends of the strip to form an endless frame of curved contour.

LOUIS KOPPERSMITH.
